(57) **CLAIM**

The ornamental design for a portion of a display panel or screen with an icon, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a first embodiment of a portion of a display panel or screen with an icon showing my new design. FIG. 2 is a front view of a second embodiment of a portion of a display panel or screen with an icon showing my new design.

FIG. 3 is a front view of a third embodiment of a portion of a display panel or screen with an icon showing my new design; and,

FIG. 4 is a front view of a fourth embodiment of a portion of a display panel or screen with an icon showing my new design.

The outer dot dash dot broken line surrounding the design represents the boundaries of the portion of a display panel or screen with an icon and forms no part thereof. The inner dot dash dot broken lines represent the boundaries of an unclaimed part of the portion of a display panel or screen with an icon and form no part of the claimed design.

1 Claim, 4 Drawing Sheets
